UNITED STATES PATENT OFFICE.

GEORGE A. LOWRY, OF INDIANAPOLIS, INDIANA, AND THOMAS K. LOWRY, OF CHICAGO, ILLINOIS.

AUTOMOBILE EXHAUST LOCK.

Application filed June 21, 1920. Serial No. 390,677.

To all whom it may concern:

Be it known that we, GEORGE A. LOWRY and THOMAS K. LOWRY, citizens of the United States, and residents of Indianapolis and Chicago, respectively, counties of Marion and Cook and States of Indiana and Illinois, respectively, have invented a certain new and useful Automobile Exhaust Lock; and we do hereby declare that the following is a full, clear, and exact description thereof, reference being had to the accompanying drawings, in which like numerals refer to like parts.

This invention relates to a lock control device for locking the exhaust of any form of engine where the elimination and discharge of the used forces are necessary for its operation.

It is the object of this invention to provide a thief proof locking mechanism for the exhaust of a motor which will withstand all tampering and prevent the opening of the exhaust, when properly locked, except by removal or mutilation.

One feature of the invention lies in the construction of the connection between the exhaust manifold and the locking mechanism, wherein the ordinary nut is replaced with a smooth surface round nut which can not be removed with the ordinary wrench but only with large pipe tongs which could not be conveniently carried around. In addition to this precaution, a further safe guard is added by placing a set screw through the nut into the manifold and cutting off the head, making it impossible to separate the locking mechanism from the manifold.

Another feature is in the means for preventing the use of a hack saw for cutting an opening between the manifold and the lock for permitting the escape of the exhaust. This consists of a loosely mounted collar mounted between the nut and the locking mechanism, and loosely mounted so that a saw cannot well be operated for cutting through into the exhaust pipe.

Another feature of the invention lies in the construction of the upright containing the valve stem and lock, whereby it is formed of light tough material and firmly welded to the exhaust pipe so that it cannot be broken off, but any mutilation thereof would effect its bending which would obstruct the unlocking of the valve. This

upright is also perforated for cooling the lock and preventing its overheating. However, the lock will be heated to a high degree, so that it is essential that the key be removed after use for locking or unlocking. 60

Still another feature of the invention is the construction of the lock wherein it is provided with two sets of tumblers so that the key can be removed when it has made a quarter turn, the valve making only a 65 quarter turn to open or close. This has also been done by means of a Geneva movement on the end of the lock so that the key could make the complete turn and the valve only a quarter turn, thereby accomplishing 70 the same result. In the construction of this lock it is absolutely essential that the key be removed at each operation, otherwise the operator could not touch it. It is, therefore, preferable that two sets of tumblers be provided wherein the key can be removed 75 without the key being retained to open or close the lock.

The full nature of this invention will be understood from the accompanying drawings and the following description and claims.

Fig. 1 is a side elevation of a portion of a motor showing the position and side elevation of the locking mechanism. Fig. 2 85 is a central longitudinal cross section through the locking mechanism. Fig. 3 is a front elevation of the locking mechanism. Fig. 4 is a central vertical section through the tumbler cylinder of the lock. Fig. 5 is 90 a section taken on the line 5-5 of Fig. 4 showing the cylinder in the unlocked position. Fig. 6 is a cross section through the tumbler cylinder showing it in locked position with the key removed. Fig. 7 is the 95 same as Fig. 6 showing the tumbler in locked position after a quarter turn with the key removed.

In the drawings there is shown a cylinder block 10 provided with a spark plug 11 mounted in the forward part of a motor vehicle, having a dash 12 and a coil box 13. The steering post 14 is mounted in the forward part of the vehicle, and a foot board 15 inclines upwardly in close proximity to 100 the motor, all of which is of the ordinary construction commonly used.

The motor is provided with an exhaust manifold 16 having a connection with the exhaust pipe 17 immediately joining the cyl- 110

inder block and to the rear thereof. The exhaust pipe 17 extends rearwardly from the motor directly beneath the foot board 15. The locking mechanism is adapted to connect or join the rear of the exhaust manifold 16 with the exhaust pipe 17 by the connecting pipe or conduit 18.

Mounted on the pipe or conduit 18 there is a connecting nut 19 having a smooth round outer surface and threaded on the interior. The nut 19 is provided with a reduced portion adapted to engage with the expanded end 20 of the pipe 18 so as to be held thereon and draw the end of said pipe 18 in direct engagement with the manifold 16. In order that the smooth surface nut 19 may be screwed on to the end of the manifold, there is a set screw 21 which may be engaged for turning the nut and then screwed there-through into engagement with the end of the manifold for securely locking said nut in position, after which the head of the set screw can be cut off so as to prevent the removal of the nut.

25 Mounted in close proximity to the nut 19 there is a butterfly valve 22 within the conduit 18 for opening and closing the same, whereby the escape of the exhaust will be prevented when it is turned to closed position. The valve 22 is operated by a valve stem 23 extending upwardly in a protecting tube 24. The valve stem is provided with a bifurcated end in which a lock stem 25 engages for turning and operating said stem 35 and valve 22. For protecting said valve stem and lock from manipulation, a perforated upright housing 26 is mounted and securely welded to the conduit 18 and is formed preferably of light material so that it cannot be broken off, and any force applied to it will only cause it to bend, thereby further preventing the valve from being turned. The perforations 27 are provided for air cooling the locking mechanism which will be heated 40 to a high degree by the exhaust gases.

50 The locking mechanism and housing extend directly upward from the conduit 18 through the foot board 16 so as to permit the lock to be readily accessible from the driving seat. In order to prevent the heat from being transmitted through the housing to the foot board, an open space 28 is provided therein about the housing and covered by a metal flanged fitting 29, supported over the foot board by an asbestos gasket 30, and closed by a hinged cap 31.

55 In order to protect the pipe 18 from being cut into by a hack saw so as to provide an outlet or escape for the exhaust gases and thereby avoiding the lock, a loose collar 32 is provided, loosely mounted on the pipe 18 and covering the entire space between the nut 19 and the upright housing 26, so loosely mounted that it will turn and give with the application of a hack saw, or any other simi-

lar cutting instrument. As the saw cannot well be operated on a loose object, said collar will not only be extremely difficult to cut, but will afford additional protection to the pipe 18 for preventing the mutilation thereof.

70 In order to leave the least possible room for a thief to operate, the device is placed close to the manifold and foot board. This results in the locking device being subjected to a very high temperature, the exhaust pipe at this point frequently becoming red hot. This necessitates the removal of the key from the lock, as if it is left therein it will become too hot to be touched by hand, and as the valve only makes a quarter turn to open or close, it is necessary to provide a special lock with two sets of tumblers so that the key can be removed when it has made a quarter turn. It being absolutely essential that the key be removed with each operation, such a lock is necessary to the operation of this mechanism.

75 From the foregoing it will be understood that the locking mechanism as herein described, is proof against being removed, against being cut into or mutilated between the manifold and the valve and also against the lock itself being tampered with or broken off, so that there is no way in which a thief 80 can unlock or break into the exhaust pipe after it has once been locked and the key removed.

85 The locking mechanism which will permit of the removal of the key upon a quarter turn of the valve, as shown in Figs. 4, 5, 6 and 7 embodies a tumbler cylinder 35 in which a key 36 extends for engaging the tumblers 37 which seat in the recesses of the key so as to lie flush with the adjacent surface of the cylinder 35 and the bolt 38, the bolt 38 extending centrally through the cylinder 35 and having secured thereto the locking stem 25. The bolt 38 is provided with the usual irregular slots 39 in which 90 the key may be inserted. The bolt 38 contains a plurality of tumblers 37, forming one set vertically aligned therein, and the cylinder 35 contains corresponding plungers 40 in two sets spaced ninety degrees from each other, said plungers being adapted to engage the tumblers 37 and exert a yielding force against them by means of the compression springs 41, so that when the key is removed the springs 41 will force the plungers 40 forwardly so that they will lie between the surfaces of the bolt 38 and cylinder 35 thereby locking the bolt and cylinder together so as to prevent the turning of the stem 25.

95 When the key is turned to a position such that the plungers and tumblers will register it may be removed, and upon its removal, the bolt will be locked. The above described lock, therefore, permits the removal of the 100

key and the locking of the device upon a quarter turn instead of the full and complete turn as is commonly necessary.

The invention claimed is:

5. 1. A locking device for a conduit, having a valve mounted therein, means for opening and closing said valve and locking it in position, means for connecting said locking device with the conduit, and an annular 10 sleeve loosely mounted thereon between said connecting means and valve for protecting said locking means against being engaged by a cutting tool.
15. 2. A locking device for a conduit, having a valve mounted therein, means for opening and closing said valve and locking it in position, and a metal housing firmly secured to and enclosing said locking device for preventing the tampering therewith, said housing being of less strength than its connection with said locking device so as to cause it to bend rather than break off.
20. 3. A locking device for a conduit, having a valve mounted in said locking device, means for opening and closing said valve and locking it in position, and a metal housing firmly secured to and enclosing said

locking device for preventing the tampering therewith, said housing being of less strength than its connection with said locking device so as to cause it to bend rather than break off, and having a plurality of 30 perforations for permitting the radiation of heat therefrom.

4. A locking device for a conduit, having a valve mounted in said locking device, means for opening and closing said valve and locking it in position, an annular nut 35 mounted on said locking device for connecting it with said conduit, means for locking said nut on said conduit, an annular sleeve loosely mounted on said locking device between said nut and valve for protecting it against being engaged by a cutting tool, and a perforated housing securely fixed to said 40 locking device for protecting said opening and closing means against mutilation and permitting the cooling thereof, substantially as described.

In witness whereof, we have hereunto affixed our signatures.

GEORGE A. LOWRY.
THOMAS K. LOWRY.
